UNITED STATES PATENT OFFICE

EDMOND B. WEBSTER, OF CLIFTON, KANSAS.

FENCE-TIGHTENER.

No. 807,589.

Specification of Letters Patent.

Patented Dec. 19, 1905.

Application filed March 3, 1905. Serial No. 248,358.

To all whom it may concern:

Be it known that I, EDMOND B. WEBSTER, a citizen of the United States, residing at Clifton, in the county of Washington and State of 5 Kansas, have invented certain new and useful Improvements in Fence-Tighteners, of which the following is a specification.

My invention relates to fence-tighteners, and has for its object to produce a tool by 10 which a wire fence can be easily and quickly tightened and which will hold the fence until it can be so secured.

A further object is to produce a device of this character which is simple, strong, durable, 15 and inexpensive of construction.

With the above-named objects in view the invention consists in certain novel and peculiar features of construction and organization, as hereinafter described and claimed, and in order 20 that it may be fully understood reference is to be had to the accompanying drawings, in which—

Figure 1 represents a perspective view of the tool as arranged preliminary to tightening 25 a wire fence. Fig. 2 is a vertical section on the line II II of Fig. 3. Fig. 3 is a top plan view of the tool. Fig. 4 is a side elevation showing the arrangement of the parts to hold the fence tightened until so secured by 30 permanent means. Fig. 5 is a detail perspective view showing the fence after being tightened and also showing the permanent means for holding the fence in its tightened condition.

In the said drawings, a metal strip or bar 35 is bent back upon itself at its middle to form a handle 1, the parts of the bar being riveted together, as at 2. At its rear end the handle is provided with a loop 3, and its front end is 40 sharpened or pointed, as at 4, and near its front end the parts of the bar are bent outward in opposite directions, as at 5, so as to form an opening, and said opening is divided longitudinally by a short bar 6, riveted between 45 parts of the handle.

7 is a bolt extending through bent portions 5 and partition 6 and engaged at one end by a retaining-nut 8, and pivoted on said bolt at the outer side portions 5 are the ratchet-toothed 50 arms 9 of such length as to project some distance beyond the front end of the handle. Pivotally mounted on the bolt between the bent portions 5 and said ratchet-toothed arms is a brace-lever, the same preferably consisting 55 of two bars 10, pivoted near their normally front ends on the bolt and provided with

outwardly-projecting shoulders 11, said bars at the opposite side of the bolt from shoulders 11 converging together and being secured, as at 12, in such relation and terminating in diverging pointed ends 13.

To tighten the wire fence, the parts are disposed as shown in Fig. 1, the pointed ends of the brace-lever being held depressed, as shown in said figure and Figs. 2 and 3, by the operator, who then placing the pointed end 4 of the handle against the post in about the same horizontal plane as the fence-strand to be tightened releases the brace-lever, this action obviously being followed by the toothed arms 65 dropping down upon the wire, because they are heavier than said lever, the latter swinging to the dotted position shown in Fig. 4. The handle is then swung pivotally upward, so as to slide the toothed arms forwardly over 70 the fence-strand until the desired teeth are engaged with the strand. The lever is then swung down to its original position, and therefore bends the strand partially around the post, as shown in Figs. 4 and 5, the strand 75 being lettered *a*. The operator then swings the brace-lever from the position shown in dotted to the position shown in full lines, Fig. 4, where it reliably holds the handle until the operator has passed a wire *b* around 80 the opposite side of the post *c* and has coiled its ends around wire *a*, so as to hold the latter in its tightened condition, as shown in Fig. 5. The tool is then removed to tighten 85 the fence at another point. 90

From the above description it will be apparent that I have produced a fence-tightener embodying the features of advantage enumerated as desirable and which obviously is susceptible of modification without departing 95 from the principle of construction involved.

Having thus described the invention, what I claim as new, and desire to secure by Letters Patent, is—

1. In a tool of the character described, a handle to bear pivotally at one end against a post, toothed arms pivotally supported from said handle and projecting beyond its front end, and a lever-brace pivotally supported from the handle and capable of supporting 100 the toothed arms in an elevated position.

2. In a tool of the character described, a handle to bear pivotally at one end against a post, toothed arms pivotally supported from said handle and projecting beyond its front end, and a lever-brace pivotally supported 105 from said handle and provided at one end

with laterally-projecting shoulders to support the toothed arms elevated and at the opposite end adapted to engage the post and brace the handle.

- 5 3. In a tool of the character described, a handle to bear pivotally at one end against a post, toothed arms pivotally supported from said handle and projecting beyond its front end, and a lever-brace pivotally supported
10 from the handle, and consisting of two similar bars bent outwardly at their front ends to

provide shoulders, and converging toward their opposite ends and riveted together, and having the ends of the converging portions pointed or sharpened. 15

In testimony whereof I affix my signature in the presence of two witnesses.

EDMOND B. WEBSTER.
